VALVE CONTROL FOR SUBSURFACE WELL TOOLS

Bernardus E. Mater, Santa Monica, Calif., assignor to Baker Oil Tools, Inc., Vernon, Calif., a corporation of California

Application August 17, 1948, Serial No. 44,743

8 Claims. (Cl. 166—11)

1

The present invention relates to well tools, and more particularly to valve mechanisms forming part of such tools, especially useful in connection with the cementing, acidizing, washing, production, etc. of oil and gas wells.

Some forms of sub-surface well tools used in the cementing of a well bore embody a valve device which is subject to the pressure of the fluid in the tubing strings connected to the well tools. The fluid pressure differential within the tubing string and well tool over the external pressure tends to maintain the valve device in closed position and renders it difficult to move the valve to open position when desired. As an example, a valve member, which moves downwardly into engagement with a cooperable valve seat, may be subjected to a hydrostatic head of cement slurry within the tubing string, which tends to keep the valve member in closed position and imposes substantial force resisting its movement to open position. Similar conditions may be encountered in wells with low fluid levels, or in which the formation is taking fluid. The hydrostatic head within the tubing string and tool on one side of the valve member would be substantially greater than the offsetting pressure acting on the other side of the valve member, resulting in the tendency for such valve member to remain in closed position.

Accordingly, it is an object of the present invention to provide a valve device in a well tool, in which the valve can be opened with comparative ease despite the presence of substantial forces, such as hydrostatic heads of fluid, tending to keep the valve closed.

Another object of the invention is to provide a valve device in a well tool, which can be maintained in open position without the danger of the valve being permitted to move inadvertently to closed position.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section through a well tool located in a well casing, with its valve device in closed position;

2

Fig. 2 is a longitudinal section, on an enlarged scale, through the valve device, with the parts in closed position;

Fig. 3 is a view similar to Fig 2, with the valve device in open position; and

Fig. 4 is a cross-section taken along the line 4—4 on Fig. 2.

The invention is disclosed in the drawings as applied to a well packer of a type designed to force fluid under pressure through the perforations of a well casing. It is to be understood, however, that it has application to any type of well tool, through which fluid flow is to be controlled.

15 Specifically, the well tool consists of a body 10, suitably secured as by threading to the lower end of a string of tubing or drill pipe 11, by means of which the tool is conveyed through the well casing 12 to the desired operating point therein. 20 The body consists of an upper body member 13, a lower body member 14, and an intermediate body member 15 connecting the upper and lower members together in spaced relation. The general type of well tool shown is a packer described and claimed in the application of Charles E. Costello, Serial No. 391,548, filed May 2, 1941, for Well Devices, now Patent No. 2,466,305.

25 The upper and lower portions of the tool are substantial duplicates, being connected to the intermediate body member 15 in opposed relation. A description of the upper portion should suffice for the lower portion as well.

30 The upper body member 13 includes an elongate mandrel or nipple 16 having a sub 17 screwed on its upper end, and a lower ported sub 18 secured to its lower end. One or more packing cups 60, 61 of rubber or similar material are suitably secured on the mandrel, with the lower cups 60 facing downwardly and the upper cup 61 facing upwardly. These packing cups are adapted for slidable sealing engagement with the wall of the well casing 12 to prevent both upward and downward flow of fluid between the upper body member 13 and the casing wall.

35 40 45 50 55 An upper by-pass tube 20 is positioned within the upper body member to provide an annular space 21 therewith. Its upper member is threaded into a by-pass T 22, which is suitably secured, as by welding, to the upper by-pass sub 17, through which it opens outwardly into the tubing-casing annulus 23 above the upper packing 61. The lower end of the by-pass tube 20 extends through an inner flange 24 on the lower sub 18, containing a rod packing 25 pressed in leakproof engagement against the exterior of the tube by a suitable packing nut 26, to prevent

downward flow of fluid through the annulus 21 beyond the flange 24.

As stated above, the construction of the lower tool portion is substantially the same as the upper, with the parts facing in the opposite direction, so that fluid passage between the lower body member 14 and casing wall in both upward and downward directions is prevented, and upward flow of fluid through the lower annulus 21a beyond the flange 24a is prevented by the flange 24a, packing 25a and packing nut 26a surrounding the lower by-pass tube 20a. For convenience in designation, the lower parts are numbered the same as the corresponding upper parts with the suffix "a" added.

The upper and lower tool portions are held together in spaced relation by the intermediate body member 15, which actually forms part of the by-pass of the tool. This intermediate body member is secured to the upper and lower subs 18, 18a and may be made of any length desired, depending upon the spacing required between the upper and lower packing cups 60, 60a. The by-pass around the packings extends from a point outside the tool below the lowermost packing 61a to a point outside the tool above the uppermost packing 61. More specifically, this by-pass passage is constituted by the lower T 22a, lower by-pass tube 20a, intermediate body member 15, upper by-pass tube 20, and upper by-pass T 22.

The upper sub 18 is provided with one or more upper outlets or ports 27 adjacent the packing cup 60 and flange 24, and the lower sub 18a is similarly provided with one or more lower outlets or ports 27a adjacent the lower packing cup 60a and flange 24a. Fluid cannot pass directly from the upper body annulus 21 to the lower body annulus 21a because of the flanges and packings around the by-pass tubes, but must pursue an indirect course. The fluid may be pumped downwardly through the tubing 11 into the upper body member annulus 21, exiting through the upper ports 27 into the localized annular zone 28 defined by the upper and lower packings 60, 60a and by the intermediate body member 15 and casing 12. This fluid may flow downwardly through the zone and enter the lower body member 14 through the lower ports 27a, where the fluid can pass downwardly through the annulus 21a around the lower by-pass tube 20a into a valve body or housing 29 screwed into the lower end of the lower sub 17a. The fluid may then pass through the valve outlets or ports 30 in the housing to the exterior of the tool 23a below the lower packing cup 61a, from where it may flow upwardly into the lower by-pass T 22a, through the lower by-pass tube 20a, intermediate by-pass member 15, tube 20, and upper by-pass T 22, into the tubing-casing annulus 23 above the upper packing cup 61.

The allowing of the fluid to pursue the course just described is dependent upon the control of the fluid flow through the valve ports 30 at the lower end of the tool. Such control is obtained through a valve mechanism including a ball valve member 70 disposed within the housing 29 and adapted to move downwardly into seating engagement with a valve seat 71 secured in the valve housing 29. The valve seat 71 is clamped between an upper valve housing portion 29a and a lower housing portion 29b threaded onto the upper portion. The ports 30 extend through the wall of the lower housing portion below the valve seat 71.

The ball 70 is elevated from its seat, to allow

fluid flow around the ball valve 70, through the seat 71 and out through the ports 30, by means of a tubular stem 72 disposed in the lower housing portion 29b and threadedly secured to a head 73, which is threadedly connected to the lower housing portion by interengaging right hand threads 74 formed on the head and the housing. A rod 75 is integral with, or otherwise secured to, the head 73 and depends through an end closure 76 secured to the housing 29b. This rod has a drag device 77 attached to it, which, in the present instance, consists of a lower collar 35 and guide 36 threaded on the rod, with a plurality of outwardly bowed drag springs 37 secured to the lower collar and extending upwardly for attachment to an upper collar 38 slidably mounted on the rod.

The drag device resists rotation of the rod 75, and of the head 73 and tubular stem 72 connected to it, within the casing 12. Thus, rotation of the tubular string 11, packer body 10 and valve housing 29 as a unit in one direction, as to the right, will effect their downward movement, or relative upward movement of the rod 75, threaded head 73 and valve stem 72 within the housing 29, in order that the upper end 72a of the stem can engage the ball valve 70 and elevate it from its seat 71. Similarly, rotation of the tubing string 11, packer body 10 and valve housing 29 in the opposite direction, or to the left, will cause the tubular stem 72 and rod 73 to shift relatively downward in the opposite direction, in which position the stem 72 becomes disengaged from the ball valve 70 and allows it to reengage its companion seat 71.

When the valve is in closed position, as illustrated in Figs. 1 and 2, fluid under pressure within the tool above the ball valve member 70 acts downwardly upon it and tends to hold it engaged against its valve seat 71. During the time that pressure is acting downwardly on the ball valve member, the latter can still be elevated from its seat by rotating the tubing string 11, packer body 10 and valve housing 29 as a unit to the right, which will cause the valve housing 29 to thread relatively downward on the rod head 73, until the ball valve 70 is removed from its seat 71. The mechanical advantage afforded by the threaded connection 74 permits a comparatively low torque or turning effort, and resistance to rotation offered by the drag springs 37 against the casing wall, to be converted into a considerably larger force of the tubular stem 72 pushing the ball valve 70 upwardly from its seat 71. Since the threaded connection 74 is self-locking, the tubular stem 72 will maintain the ball valve from its seat, despite the tendency of downwardly directed fluid forces to keep the ball 70 on its seat 71.

A representative use of the valve mechanism in question is in connection with the cementing of a casing. The tool disclosed in Fig. 1 is lowered through the well casing 12 until the inner packing cups 60, 60a are disposed on opposite sides of casing perforations 59, through which cement slurry or other cementitious material is to be ejected. During this running-in operation, if desired, the rod head 73 may be disposed in an upper position within the housing, in order that the stem 72 will hold the ball valve 70 from its seat 71. This permits the well fluid to flow through the ports 30 and upwardly through the tool, as well as in a reverse direction. Even with the ball valve 70 on its seat 71, and with the rod 75 and stem 72 in a lower position within the

housing 29, the fluid could still flow upwardly through the tool by automatically unseating the ball valve 70.

With the packing cups 60, 60a disposed on opposite sides of the casing perforations 59, the tubing string 11, and packer body 10 and housing 29 connected thereto, are rotated to the right. Since the drag springs 37 resist rotation of the rod 75 and tubular stem 72, the latter are caused to shift relatively in an upward direction until the stem 72 engages the ball 70 and elevates it from its seat 71. Circulating fluids may be pumped down the tubing string 11 with the valve in open position, as illustrated in Fig. 3, passing through the upper annulus 21 and out through the upper ports 27 into the localized zone 28 between the packing members 60, 60a, thence into the lower ports 27a and lower annular passage 21a. From this passage, the fluids flow into the valve housing 29, around the ball valve 70, through the valve seat 71, and out through the ports 30 to a point below the lowermost packing members 61a. The fluid then may proceed upwardly through the by-pass passage 22a, 20a, 15, 20, 22, discharging into the tubing-casing annulus 23 above the upper packing member 61 for continued upward movement through such annulus to the top of the well bore.

A charge of cement slurry may be started down the tubing string 11 and when its lower end is near the well tool, the tubing string 11 is rotated to the left several revolutions, in order to relatively feed the non-rotating rod 75 and tubular stem 72 downwardly of the housing 29 to a position in which the valve ball 70 may engage its seat 71, thus closing the valve and the ports 30 to passage of fluids between the interior of the well tool and the exterior of the well tool below the lowermost packing 61a.

The cement slurry passes from the lower end of the tubular string 11, through the upper annulus 21 in the body and out through the upper ports 27, being forced under pressure through the casing perforations 59 for disposition behind the well casing 12. Such cement slurry cannot flow through the lower ports 27a into the lower body member 14, since the valve is in closed position and fluid in the lower portions of the body member 14 is prevented from passing downwardly and out through the ports 30.

Following the deposition of the required amount of cement slurry through the perforations 59, the tubing string 11, body 10 and valve housing 29 may be rotated to the right, in order to effect relative upward feeding of the rod 75, cause the stem 72 to engage the ball valve 70 and elevate it from its seat 71. This opens the ports 30 and allows washing fluid to be pumped down the tubing string 11, forcing any excess cement slurry in the tubing string ahead of it. This slurry is caused to flow through the upper annulus 21 and upper port 27 into the localized zone 28, then through the lower port 27a and lower annulus 21a, from where it passes around the ball valve 70 and through the seat 71, exhausting through the valve ports 30. Such excess cement slurry, followed by the washing fluid, tially down through the tubing-casing annulus 15, 20, 22, into the annulus 23 above the upper packing 61, for passage to the top of the well bore and appropriate disposal.

The excess cement slurry may also be disposed of by circulating the washing fluid in a direction reverse to that described. The fluid passes initially down through the tubing-casing annulus

23, through the by-pass passage and the ports 30 for upward flowing around the valve member and through the body passages 21a, 21 and ports 27a, 27 into the tubing string 11. The excess cement slurry is carried upwardly through the tubing string to the top of the well bore.

In the event that the excess cement slurry is to be disposed of by pumping the washing fluid down the tubing string, conditions sometimes render it difficult to move or elevate the valve member 70 to open position. As an example, in the event that there is an extended column of excess cement slurry present in the tubing string of a thousand feet, the hydrostatic head of such cement slurry acting downwardly on the ball valve member 70 exerts a substantial downward closing force thereon. This force may be substantially greater than the friction force of the drag springs 37 against the wall of the well casing 12. Despite this overbalancing of forces tending to keep the valve closed, the latter may still be elevated readily because of the multiplication of the turning effort of the tubing string 11, body 10 and housing 20 on the tubular stem 72, through the threaded interconnection 74 between the rod head 73 and the valve housing 29b.

When in its upper position, the stem 72 holds the ball valve 70 from its seat 71, and allows the tubing string 11 and well tool to be elevated in the well casing 12 without danger of the ball valve 70 reengaging its seat. The threaded interconnection 74 is self-locking, and will not permit downward movement of the rod 75 and tubular stem 72 unless the tubing string 11 is rotated in the proper direction. Assurance is therefore had that the valve member 70 will remain in open position whenever desired, as during downward pumping of fluids through the well tool to remove excess cement slurry from the tubing and tool, or during elevation of the tool within the casing string.

It is, accordingly, apparent that a valve device for a well tool has been disclosed which can be opened against a comparatively high pressure differential, tending to keep it in closed position readily through the simple expedient of rotating the tubing string. In addition, the valve can be maintained in open position whenever desired without danger of its inadvertent closing.

The inventor claims:

1. In a well tool: tubular means adapted to be lowered in a well conduit and having an outlet; a valve seat in said tubular means above said outlet; a valve member movable downwardly into engagement with said seat; rod means in said tubular means and depending from said tubular means; said rod means being adapted to act upon said member to elevate it from said seat; means providing a threaded connection between said rod means and tubular means; a drag device connected to said rod means and frictionally engageable with said conduit; stop means detachably secured to said tubular means; and stop means on said rod means engageable with the stop means on said tubular means to limit the extent of lowering movement of said rod means relative to said tubular means.

2. In a well tool: tubular means adapted to be lowered in a well bore and having an outlet; a valve seat in said tubular means above said outlet; a ball valve member movable downwardly into engagement with said seat; instrumentalities threadedly connected to said tubular means and engageable with said ball valve member for lifting it from said seat in response to rotation of said tubular means; a drag device connected to

said instrumentalities and frictionally engageable with said conduit; stop means detachably secured to said tubular means; and stop means on said instrumentalities engageable with the stop means on said tubular means to limit the extent of lowering movement of said instrumentalities relative to said tubular means.

3. In a well tool: tubular means adapted to be lowered in a well conduit and having an outlet; a valve seat in said tubular means above said outlet; a ball valve member movable downwardly into engagement with said seat; rod means in said tubular means engageable with said ball valve member to lift it from said seat, said rod means depending from said tubular means; means providing a threaded connection between said rod means and tubular means; a drag device connected to said rod means and frictionally engageable with said conduit; stop means detachably secured to said tubular means; and stop means on said rod means engageable with the stop means on said tubular means to limit the extent of lowering movement of said rod means relative to said tubular means.

4. In a well tool: tubular means adapted to be lowered in a well conduit and including a valve housing provided with an outlet; a valve seat in said housing above said outlet; a valve member movable downwardly in said housing into engagement with said seat; rod means in said housing engageable with said valve member to lift it from said seat; means providing a threaded connection between said rod means and housing; a closure detachably secured to said housing and through which said rod means extends; means on said rod means engageable with said closure to limit the extent of lowering movement of said rod means relative to said housing; and a drag device connected to said rod means below said closure and frictionally engageable with said conduit.

5. In a well tool: tubular means adapted to be lowered in a well conduit and including a valve housing provided with an outlet; a valve seat in said housing above said outlet; a valve member movable downwardly in said housing into engagement with said seat; rod means in said housing engageable with said valve member to lift it from said seat; means providing a threaded connection between said rod means and housing; a closure detachably secured to said housing and through which said rod means extends; means on said rod means engageable with said closure to limit the extent of lowering movement of said rod means relative to said housing; and means connected to said rod means below said closure for enabling said housing to be rotated relative to said rod means.

6. In a well tool: tubular means adapted to be lowered in a well conduit and including a valve housing provided with an outlet; a valve seat in

said housing above said outlet; a ball valve member movable downwardly in said housing into engagement with said seat; rod means in said housing separate from and engageable with said ball valve member to lift it from said seat; means providing a threaded connection between said rod means and housing; a closure detachably secured to said housing and through which said rod means extends; means on said rod means engageable with said closure to limit the extent of lowering movement of said rod means relative to said housing; and means on said rod means below said closure for enabling said housing to be rotated relative to said rod means.

15 7. In a well tool: tubular means adapted to be lowered in a well conduit and including a valve housing provided with an outlet; a valve seat in said housing above said outlet; a valve member movable downwardly in said housing into engagement with said seat; rod means in said housing engageable with said valve member to lift it from said seat; means providing a threaded connection between said rod means and housing; a closure detachably secured to said housing and through which said rod means extends; said threaded connection including a head threaded in said housing above said closure and engageable with said closure to limit the extent of lowering movement of said rod means relative to said housing; and a drag device connected to said rod means below said closure and frictionally engageable with said conduit.

20 8. In a well tool: tubular means adapted to be lowered in a well conduit and including a valve housing provided with an outlet; a valve seat in said housing above said outlet; a valve member movable downwardly in said housing into engagement with said seat; rod means in said housing engageable with said valve member to lift it from said seat; means providing a threaded connection between said rod means and housing; a closure detachably secured to said housing and through which said rod means extends; said threaded connection including a head threaded in said housing above said closure and engageable with said closure to limit the extent of lowering movement of said rod means relative to said housing; and means on said rod means below said closure for enabling said housing to be rotated relative to said rod means.
